UNITED STATES PATENT OFFICE.

EDWARD C. HANSON AND BURT E. HALLQUIST, OF MINNEAPOLIS, MINNESOTA, AS-SIGNORS TO O. B. MCCLINTOCK COMPANY, OF MINNEAPOLIS, MINNESOTA, A CORPORATION OF MINNESOTA.

DESIGN FOR AN ENTRANCE DOOR FOR A DEPOSITORY.

Application filed September 2, 1927. Serial No. 23,279. Term of patent 14 years.

To all whom it may concern:

Be it known that we, EDWARD C. HANSON and BURT E. HALLQUIST, citizens of the United States, residing at Minneapolis, in the county of Hennepin and State of Minnesota, have invented a new, original, and ornamental Design for Entrance Doors for Depositories, of which the following is a specification, reference being had to the accompanying drawing, forming part thereof.

The single view of the drawing is a perspective view of the entrance door for a depository, showing our new design.

We claim:

The ornamental design for an entrance door for a depository, as shown.

EDWARD C. HANSON.
BURT E. HALLQUIST.
